(57) **CLAIM**

The ornamental design for a shoe rack for shoe management apparatus, as shown and described.

DESCRIPTION

FIG. 1 is a front perspective view of the shoe rack for shoe management apparatus showing our new design;

FIG. 2 is a front view thereof;

FIG. 3 is a back view thereof;

FIG. 4 is a left side view thereof;

FIG. 5 is a right side view thereof;

FIG. 6 is a top plan view thereof;

FIG. 7 is a bottom plan view thereof;

FIG. 8 is a front perspective view showing the state of use that the claimed design has been installed at inside of the shoe management apparatus; and,

FIG. 9 is a front perspective view showing the state of use that the claimed design has been stored at the door of the shoe management apparatus.

The portions of FIGS. 8 and 9 drawn in broken lines show environmental structure only and form no part of the claimed design.

1 Claim, 9 Drawing Sheets
